UNITED STATES PATENT OFFICE.

WILLIAM T. ADAMS, OF READING, PENNSYLVANIA.

CLOTHES-TREE OR THE LIKE.

1,187,956.

Specification of Letters Patent. Patented June 20, 1916.

Application filed June 19, 1915. Serial No. 34,984.

To all whom it may concern:

Be it known that I, WILLIAM T. ADAMS, a citizen of the United States, residing at Reading, in the county of Berks and State of Pennsylvania, have invented certain new and useful Improvements in Clothes-Trees or the like, of which the following is a specification.

My invention relates particularly to vertical-column stands or supports such as "clothes trees"; and it consists in providing an improved construction in which separate bracket-arms are simply connected in series to the central column member so as to form rigid supporting means at the bottom of the column, or in determined position upon the latter, as fully described in connection with the accompanying drawing, the novel features being specifically pointed out in the claims.

A main object of my invention is to provide a knock-down construction comprising separate easily produced parts adapted to be easily assembled in a rigid and ornamental supporting structure, and it is best illustrated as applied in the accompanying drawings where separate attached series of bracket-arms are made to form respectively a supporting base for the column, and supporting hooks upon the upper portion of the latter.

Figure 1 is a general view of the complete device. Fig. 2 is an enlarged sectional plan view, on the line 2—2 of Fig. 1. Fig. 3 is a sectional elevation on the line 3—3 of Fig. 2. Fig. 4 is a separate view of the modified form of clamping sleeve employed for the upper series of bracket-arms.

The central column 5 is preferably formed by a piece of round tubing cut to desired length and provided with a cap 6 at its upper end. The supporting base for the column is formed by a series of separate bracket-arms 7, which are rigidly assembled in a clamping sleeve 8 inclosing the lower portion of the column, while another series of bracket-arms 7^a are shown similarly secured to the upper portion of the column by another clamping sleeve 8^a to serve as supporting hooks.

The lower clamping sleeve 8 differs from the upper one 8^a merely in being of conical or downwardly-flared form; and the lower bracket-arms 7 differ from the upper ones 55 7^a mainly in having their pocket-engaging

portions 10 tapered to correspond with the flared form of the sleeve 8. In each case these sleeves have a central passage way 11 of somewhat larger size than the column 5 so as to permit free sliding movement of the latter; and a series of symmetrically arranged radially-extending pockets 12 open to said central passage way 11 and each adapted to receive the engaging portion of a bracket arm.

The opposing side walls 13, 13 of each of these pockets are so spaced as to loosely receive the engaged portion 10 of a bracket-arm; and when the outer face 14 of the latter is seated against the outer wall of the pocket its inner face is adapted to project slightly into the central passage way 11 so as to insure contact with the wall of the column 5 when the latter is in place. In order that this contact may be such as to produce a tilting effect on each bracket-arm when the parts are clamped together, this inner face is made eccentric to the wall of the column so that its line of contact, 15, with the latter will be located to one side of the radial line 16—16 of the pocket. The clamping of the parts is effected as indicated by a single clamping screw 18 extending through a screw threaded opening 19 in the wall of the sleeve and adapted to bear upon the rear face of one of the pocket-engaged bracket-arms. Each of the latter is formed with a positioning shoulder 22 which rests upon the edge of the engaged sleeve, as indicated.

The base-forming bracket-arms 7, are formed as shown with an offset 20 which serves as a support or stop for the column 5 when the parts are assembled. In doing this the series of arms 7 are loosely placed in the respective pockets 12 of the sleeve, and the end portion of the column 5 is then inserted into the latter, in loose contact with the inner faces of the grouped arms, until stopped by the supporting offsets 20. By merely tightening up the clamping screw 20 against one of the bracket-arms all the parts are simultaneously pressed tightly together. Because of the contact line 15 of each arm with the column being located to one side of the radial center-line 16 of the pocket, the arm is tilted in the pocket, as indicated in Fig. 2, so as to insure tight contact with the latter at a diagonally opposite portion, whereby satisfactory tightness of the connections is insured.

It will be readily seen that all the parts of my improved device are simply and cheaply produced, and that they may be conveniently shipped in knock-down form, 5 and easily assembled in a neat and rigid structure.

The particular form and function of the arms employed may obviously be varied.

What I claim is:

10. 1. A stand comprising a vertical column, a clamping-sleeve slidable thereon and provided with a series of interior radially-extending pockets, a corresponding series of separate bracket-arms engageable in said radial pockets, and a clamping screw adapted to simultaneously seat the engaged bracket-arms against said column.
15. 2. A stand comprising a vertical column, a clamping-sleeve slidable thereon and provided with a series of interior radially-extending pockets, a series of bracket-arms each provided with a pocket-engaging portion having an inner face adapted to contact with the column to one side of the radial 20 center line of the pocket, and means for
25. 3. A stand comprising a vertical column, a clamping-sleeve slidable thereon and provided with a series of interior radially-extending pockets, a corresponding series of separate bracket-arms engageable in said radial pockets, and provided with column-supporting offsets, and means for seating the engaged bracket-arms rigidly against the column.

seating the engaged bracket arms rigidly against the column.

3. A stand comprising a vertical column, a clamping-sleeve slidable thereon and provided with a series of interior radially-extending pockets, a corresponding series of separate bracket-arms engageable in said radial pockets, and provided with column-supporting offsets, and means for seating the engaged bracket-arms rigidly against the column.

4. A stand comprising a vertical column, a plurality of clamping-sleeves slidable thereon and each provided with a series of interior radially-extending pockets, separate series of separate bracket-arms engageable respectively in the radial pockets of the respective sleeves, and means for seating the engaged bracket-arms of each series rigidly against the column; the bracket-arms of one of said series being provided with column-supporting offsets.

In testimony whereof I affix my signature.

WILLIAM T. ADAMS.
